UNITED STATES PATENT OFFICE.

SIMON I. GOLDSTEIN, OF BALTIMORE, MARYLAND.

UMBRELLA-TAG.

1,289,156.

Specification of Letters Patent. Patented Dec. 31, 1918.

Application filed November 6, 1914, Serial No. 870,582. Renewed November 22, 1918. Serial No. 263,784.

To all whom it may concern:

Be it known that I, SIMON I. GOLDSTEIN, a citizen of the United States, residing at Baltimore, in the State of Maryland, have 5 invented certain new and useful Improvements in Umbrella-Tags, of which the following is a specification.

This invention relates to tags, and more particularly to a method of attaching tags 10 to umbrellas.

The object of the invention is to provide simple and efficient means for attaching tags to umbrella sticks during the process of manufacture.

15 In order that the invention may be readily understood, reference is had to the accompanying drawings, forming part of this specification, and in which,

Figure 1 is a fragmentary view of the 20 upper end of an umbrella stick and handle, showing one of my improved tags in position on the stick; and,

Fig. 2 is a view of the tag itself.

It is proposed to provide a tag which may 25 be attached to the umbrella stick by the manufacturer, such tag bearing on one side the manufacturer's name, and on the other side, the name and address of the dealer and a place for the name and address of the 30 purchaser. The idea is that a purchaser upon buying an umbrella, fills in his name and address and the date of purchase, and then retains the tag for identification. Should the umbrella prove unsatisfactory or 35 defective, it is proposed that the purchaser can obtain a new one by presenting the tag to the manufacturer.

Referring to the drawings in detail, 1 designates the usual umbrella stick, which is 40 preferably made of metal, and 2 the handle, of any desired design. This handle is, of course, of considerably larger diameter than the stick, and is provided with a socket (not shown) in its end, into which the end of the 45 stick is inserted and cemented.

3 designates the usual slide, and my improved tag is designed to be attached to the

stick between this slide and the handle. The tag is designated by the reference character 4 and as shown in Fig. 2, may conveniently 50 be elongated or pear-shaped in outline. At one end, the tag is provided with an opening 5, which is slightly larger than the umbrella stick 1, so as to be capable of sliding thereover, and, at the same time, is 55 smaller than the diameter of the handle 2. At 6 is indicated the place for the name and address of the dealer and purchaser, and the date of purchase. The name of the manufacturer preferably appears on the reverse 60 side. This tag may be made of tag-board, or sized fabric of any suitable kind.

In practice, the opening 5 of one of these tags is fitted over the upper end of the stick 1 before the handle is attached, and the handle then secured in position. It will be seen, therefore, that the tag is confined between the slide 3 and the handle 2, and is retained on the stick by the latter.

It will be seen that the above construction 70 affords a cheap and convenient method of securing the tag in position, and, at the same time, permits of its being readily torn off by the purchaser. The tag may, of course, contain any desired printed matter, and, while 75 adapted to other purposes, is particularly designed for use in connection with the above described guarantee system of a manufacturer.

What I claim is:

80 A device of the class described comprising a tag having an opening adapted to be threaded upon an umbrella stick before the handle is attached thereto, said opening being smaller than such handle, whereby the 85 tag is adapted to be retained on the stick by the handle.

In testimony whereof I have affixed my signature, in presence of two witnesses.

SIMON I. GOLDSTEIN.
